LADDER

Sterling P. Moore, New Madrid, Mo.

Application July 25, 1941, Serial No. 404,069

2 Claims. (Cl. 228—63)

This invention relates to stepladders and more particularly to an attachment therefor so that the legs of the ladder may be extended where a ladder of material length is desired, and whereby also the ladder may be levelled when used on uneven ground or similar surface.

Briefly the invention consists in providing each of the several legs of the ladder with an extension member, with the leg and its associated extension member complementarily equipped whereby the extension member may be readily secured at the desired position of adjustment longitudinally with respect to the leg of the ladder, to the end that the legs of the ladder may be varied in length as desired and as the surface upon which the ladder is disposed may require.

The invention together with its objects and advantages will be best understood from a study of the following description taken in connection with the accompanying drawings wherein:

Figure 1 is a side elevational view of a ladder embodying the features of the present invention.

Figure 2 is a front elevational view thereof.

Figure 3 is an enlarged fragmentary elevational view of a ladder leg and its extension, and showing the means for securing the extension at the desired position of adjustment relative to the associated leg.

Figure 4 is a fragmentary elevational view of a portion of a leg of a ladder illustrating certain features hereinafter more fully referred to.

Figure 5 is a fragmentary elevational view of a leg extension and showing the corrugated surface provided thereon.

Figure 6 is a detail sectional view taken substantially on the line 6—6 of Figure 1.

Referring more in detail to the drawings it will be seen that in accordance with the present invention each of the front legs 5 and each of the rear legs 6 has secured to the outer side thereof several, in the present instance two plates 7 positively secured to the leg through the medium of fastening elements 8 and integral barbs or projections 9 that are embedded in the leg of the ladder as shown to advantage in Figure 3.

Each plate 7 is corrugated, as also shown to advantage in Figure 3, to provide a roughened gripping surface.

Also each plate 7 at the upper edge thereof has formed integral therewith substantially C-shaped spring fingers 10, and each leg is provided with recesses 11 into which the spring fingers 10 are flexed when the leg extension 12 is secured in

positive engagement with the associated ladder-leg.

For each of the legs 5 and 6 there is provided a leg extension 12 and the same on one side thereof has a roughened or corrugated surface 13 elongated longitudinally thereof and complementing the roughened or corrugated surfaces of the plates 7 to coact therewith in securing the leg extension 12 at the desired position of adjustment longitudinally of the associated ladder leg.

Further, each of the ladder legs has extending laterally therefrom through an opening provided therefor in the plate 7 a bolt 14, and to accommodate the bolts 14 each leg extension 12 is provided with a longitudinal slot 15 as shown.

Wing-nuts 16 are threadedly engaged with the bolts 14 and when threaded home on the bolts serve to maintain the surfaces 13 of the leg extensions 12 in engagement with the corrugated surfaces of the plates 7, and the leg extensions 12 at the desired position of adjustment relative to the legs 5 and 6 of the ladder.

When a leg extension 12 is in such positive engagement with the ladder leg, 5 or 6 as the case may be, the spring fingers 10 are held in tensioned position within the recesses 11. Obviously, when incidental to an adjustment of a leg extension 12, nuts 16 are loosened, the spring fingers 10 will act on the extensions 12 to urge the same laterally away from the associated legs of the ladder, and substantially to the position shown in Figure 3, whereupon the extension 12 may then be shifted longitudinally in the desired direction relative to the associated ladder leg, after which the nuts 16 are then threaded home on the bolts 14 to urge the surface 13 of the extension 12 into engagement with the surfaces of the plates 7 whereupon the extension 12 is then rigidly secured in position of adjustment.

In Figure 1 there is illustrated, in phantom lines, the manner in which the attachment may be used to advantage in levelling a ladder when the same is used on an inclined or uneven surface.

It is believed that the many advantages of an invention of this character will be had by those skilled in the art without further detailed description.

It is also to be understood that I am well aware that in practical fields, changes may be made without departing from the spirit of the invention, and accordingly claim all such forms of the invention to which I am entitled.

Having thus described the invention what is claimed as new is:

1. As a new article of manufacture, a ladder having extensible legs, interengaging means on the opposed faces of the extensions and the legs, means for securing the extensions in longitudinally adjusted position relative to the legs, and spring means formed as a part of said interengaging means and yieldably urging the extensions laterally away from said legs.

2. As a new article of manufacture, a ladder, each leg of which is provided on one face thereof with a corrugated surface, an extension for each leg of the ladder, each extension having a corrugated surface complementing the corrugated surface of its associated ladder leg for coaction therewith in securing the extension at the desired

position of adjustment longitudinally relative to the ladder leg, each leg also having at least one bolt extending laterally therefrom, and each leg extension provided with a slot accommodating the bolt and a nut threaded on the bolt and adapted to be threaded home against the extension to secure the extension at the desired position of adjustment with the corrugated surface thereof in engagement with the corrugated surface of the associated ladder leg, and spring fingers disposed above the corrugated surface of each leg and impinging on the extension for yieldably urging the extension laterally away from the ladder leg.
